SINKER CAM FOR KNITTING MACHINES

Robert H. Lawson and William L. Smith, Jr., Pawtucket, R. I., assignors to Hemphill Company, Central Falls, R. I., a corporation of Massachusetts

Application August 4, 1936, Serial No. 94,217
In Canada September 27, 1935

7 Claims. (Cl. 66—108)

This case deals with improvements in sinker cams for knitting machines wherein the sinkers are movable in opposition to the movement of the needles for participating in stitch drawing. 5 More specifically, the invention comprises certain attachments for use with a sinker cam of the type described to take up excessive movement of the sinker due to improper fitting of parts, wear, etc.

10 In the drawings:

Fig. 1 is a section showing a typical machine of the type wherein the invention is employed;

Fig. 2 is a plan view showing a sinker cam assembly for the machine illustrated in Fig. 1, 15 the invention being illustrated therewith;

Fig. 3 is an elevation of a sinker cam and the sinker pressing spring functioning therewith;

Fig. 4 is a section through the cam illustrated in Fig. 3;

20 Figs. 5 and 6 are details of the sinker pressing spring;

Figs. 7, 8 and 9 illustrate a modified form of the invention;

Figs. 10 and 11 illustrate another modification; 25 and

Figs. 12 and 13 show in detail the pivot about which the pressing spring of the last modification swings.

Referring to Figs. 1 and 2 we have illustrated 30 certain essential parts of a multi-feed knitting machine wherein needles and sinkers move in opposed directions for the purpose of measuring and drawing stitches when forming knitted fabric. In these illustrations a rotatable needle cylinder is shown at 1, needles 2 and jacks 3 being 35 arranged for reciprocation in slots therein which are made up of hardened strips one of which is illustrated at 4. It is not necessary that the needle cylinder be built up in this manner, neither is the invention limited to rotating needle cylinders but may be employed in machines 40 wherein the cylinder is stationary with cams rotating relatively thereto. A supporting ring 5 is clamped in the usual manner to rotate with 45 the cylinder and has slots therein in alignment with other slots in a stitch ring 6, sinkers 7 being guided within these slots to pivot at the base of the shank when drawing stitches and for moving radially at the proper time. Each of these 50 sinkers has a lower projection 8 to which the upper ends of jacks connect.

A cam block generally designated at 9 has cams 10 and 11 for engaging needle butts and causing those needles to draw stitches. Said block also has attached thereto cams 12 and 13 for engag-

ing butts on the jacks to move them at the proper time for causing sinkers to participate in this stitch drawing movement. For a complete disclosure of these cams and their function reference is made to United States application No. 5 34,579, filed in the names of Lawson and Smith.

A sinker cam assembly is attached by means of screws 14 to the upper end of said cam block 9 and consists of a plate 15, an angular portion 16 and cams attached thereto. One cam 17 is fixed 10 to the inner end of plate 15 by means of screws 18. Another cam 19 is fixed to a lever 20 which pivots about point 21 for the purpose of being adjusted by means of a thumb nut 22 threaded on spindle 23, said spindle terminating at the 15 inner end in a head portion 24 for engaging cam 19. A spring 25 keeps this head 24 in engagement with cam 19 and will project that cam in towards the central part of the machine as far as the adjustment of thumb nut 22 will permit. 20 This adjustment is similar to that described in the United States application above mentioned and will not be described to greater extent in this case.

Another cam 26 is pivoted at 27 to a lever 28 25 which is in turn capable of rotating about the shoulder screw 29 on lever 20. This cam 26 bears against butts 30 on the sinkers and maintains them in an inward direction after they have passed beyond cams 17 and 19. An eccentric 31 30 is rotatable on screw 32 and also capable of being locked in position by the same, this eccentric bears against lever 28 for the purpose of adjustably limiting the movement of that lever and cam 26 inwardly of the machine. Lever 28 has an ex- 35 tension 33 to which has been attached a collar 34. A spring 35 attaches to pin 36 and to collar 34 for holding the cam 26 inwardly as far as the adjustment of eccentric 31 will permit. By movement of collar 34 along the arm 33 it is 40 possible to vary the tension in spring 35.

While drawing stitches the needles are compelled to move in a restricted pathway by means of cams 10 and 11; sinkers 7 are at the same time moved in the reverse direction by means of cams 45 12 and 13 but the movement given sinkers involves much greater acceleration than does the movement of needles. When sinkers, jacks 3 and cams 12 and 13 are new and thus fitted to very 50 close limits, there will be an exact movement of sinkers such as was contemplated by the designer of the machine. However, it is inevitable that the cams as well as the nibs on the upper end of the jack which engage about projection 8 55

and the projection itself will wear to some extent thus creating a possibility of sinkers moving throughout a greater extent than was originally planned. The inertia of the rapidly moving sinkers causes them to move farther than the jacks actually raise them; this is especially true in the machine illustrated since the fabric does not hang on the sinkers. This movement generally termed "firing" will vary for each cam spaced about the multi-feed machine, for different amounts of wear between jacks and co-operating sinkers, due to varying amounts of friction and for other reasons. Cam 17 normally fits rather closely on the tops of sinker shanks but it is necessary to have sufficient clearance at this point so that no binding will ever take place. For these reasons we have constructed a spring 37 of particular shape to attach to cam 17 and bear upon the tops of these sinker shanks.

This spring 37 is better shown in Figs. 5 and 6 and is attached to cam 17 by means of the same screws 18 which pass through plate 15 and thread into the cam. This spring has a forward slant edge 38 and a lower part 39 which inclines as shown in Fig. 6 when relieved of tension. The cam 17 is cut away as shown at 40 so that the portion 39 of the spring may fit therein if necessary due to being flexed upwardly to an excessive degree. In Fig. 4 plate 15 and cam 17 are shown in section while the spring is shown in its normal position as a series of sinkers are passing beneath it.

It will be evident from the foregoing that spring 37 will not interfere with the normal action of other elements but will always serve to limit the upward movement of sinkers as governed by the jacks, and will prevent any firing of sinkers which has proved to be a very troublesome cause of knitting streaked fabric due to the unevenness of stitch drawn.

Referring to Figs. 7, 8 and 9 we will describe a modified form of the invention wherein a cam 17' similar to cam 17 is attached to a plate 15'. This cam 17' is cut away in the same manner cam 17 was and a spring 41 having an upturned portion 42 fits beneath this cut out portion to serve the same purpose which was served by spring 37. A leaf spring 43 is attached by screw 44 to the plate and is slotted at its free end to engage the upturned part 42 as illustrated. A projection 45 has an adjusting screw 46 threaded therethrough and bearing against the top of the plate to adjust the elevation of the leading edge of spring 41. Leaf spring 43 provides for this leading edge of the sinker pressing spring moving upwardly if such movement becomes essential. A lock nut 47 serves to maintain the adjusting screw 46 in whatever position it is set.

A coil spring 48 is attached at the upper end of the upturned portion 42 and also to a pin 49 fixed in the cam. This spring is under sufficient tension to rock the pressing spring 41 about the slot in the end of leaf spring 43 thus tending to cause the tail of spring 41 to bear downwardly against the tops of sinkers. It will be seen that this spring 41 will serve to hold sinkers downwardly to prevent firing as previously described.

Referring to Figs. 10, 11, 12 and 13 a second modification is shown wherein plate 15" has attached thereto a cam 50 slightly different from cam 17 but serving the same purpose. This cam 50 is cut away in the manner described with respect to those previously mentioned but has a forward end slotted in both a vertical and horizontal direction. Within the vertical slot an up-

turned portion 51 of a spring 52 is free to pivot about a pin 54 passing through the horizontal slot. Pin 54 is cut away as illustrated in Figs. 12 and 13 so that the upturned portion 51 can be soldered or otherwise connected to the pin, and will rock thereon as the pin rotates in its horizontal slot. A hooked end 55 has attached thereto a spring 56 the other end of which is secured to pin 57; this spring serves to rock this sinker pressing spring in a direction to make it bear 10 downwardly on sinkers for the same reason disclosed with respect to springs 38 and 41.

This invention has been described with respect to a multi-feed machine of a particular type merely for illustrative purposes and it is to be understood that we are not limited particularly to multi-feed machines nor are we limited to sinkers operated by jacks of the particular type herein disclosed, but the invention may be employed with any knitting machine wherein sinkers 20 participate in the drawing of stitches and there is a possibility of firing as previously described.

What we desire to protect as our invention is defined in the claims appended hereto.

We claim:

1. In a knitting machine, a series of needles and sinkers functioning to draw loops and knit fabric, said sinkers being moved upwardly to participate in measuring and drawing said loops, jacks connected at their upper ends to said sinkers and having butts at their lower ends for engaging said cams for giving to said sinkers a predetermined amount of upward movement, and resilient means functioning on the tops of said sinkers for preventing movement beyond that originally provided by said jacks.

2. A sinker cam assembly for use with knitting machines of the type described including a cam positioned to bear upon upper surfaces of sinkers, said cam having an inclined leading edge and a spring member attached to said cam and presenting an elongated surface beneath the cam for resiliently pressing downwardly upon said sinkers.

3. A sinker cam as defined in claim 2, wherein said spring member is inclined to correspond with the inclined edge of the cam itself and wherein the portion of said cam bearing upon sinkers inclines downwardly when untensioned.

4. A sinker cam assembly for use with knitting machines of the type described including a cam for bearing upon the upper surfaces of sinkers, a spring member pivoted at the leading edge of said cam and resilient means for rocking said spring member about its pivot for the purpose of pressing said spring member downwardly against the upper surfaces of sinkers.

5. A sinker cam as defined in claim 4, further characterized in that the leading edge of said spring member is also pressed downwardly by a second resilient element.

6. A sinker assembly for use with knitting machines of the type described including a support, a cam for bearing on the upper edges of sinkers, a pivot at the forward or leading edge of said cam, said pivot being provided with a slot within which a spring-like element may slide vertically and at the same time may rock on said pivot, a spring-like element bearing within said pivot and extending upwardly therefrom and also in a horizontal direction and a spring connected to said support and to the upper end of said spring-like element for pressing the horizontal portion thereof against the upper edges of sinkers.

7. A sinker cam assembly for use in knitting machines of the type described including a support, a cam for bearing upon the upper edges of sinkers, a slot cut lengthwise along the lower surface of said cam and a resilient element attached to said cam and support having an extension

passing beneath said cam and bearing upon the upper surfaces of sinkers and so constructed that upon abnormal distortion said element will move upwardly within said slot.
